UNITED STATES PATENT OFFICE.

CHARLES W. BREED, OF CHICAGO, ILLINOIS, ASSIGNOR TO THE P. & M. CO., OF CHICAGO, ILLINOIS, A CORPORATION OF ILLINOIS.

ANTICREEPER FOR RAILS.

1,075,187.

Specification of Letters Patent. Patented Oct. 7, 1913.

Application filed June 22, 1912. Serial No. 705,259.

To all whom it may concern:

Be it known that I, CHARLES W. BREED, a citizen of the United States, residing at Chicago, in the county of Cook and State of Illinois, have invented new and useful Improvements in Anticreepers for Rails, of which the following is a full, clear, concise, and exact description, reference being had to the accompanying drawing, forming 10 a part of this specification.

My invention relates to means for preventing the creeping of rails.

The object of my invention is to provide an improved anti-creeper which is joined 15 to the rail by welding.

In the accompanying drawings I have illustrated two embodiments of my invention. I do not limit myself to these embodiments, however.

20 Figure 1 is a perspective view of an anti-creeper in which a member is welded to the upper side of the rail base and is secured to the tie by spikes. Fig. 2 is a modification of the preceding anti-creeper, the welded 25 member having depending lugs which engage the side of the tie.

In both the figures of the drawings the usual cross-tie is indicated by reference numeral 1, and the rail is indicated by reference 30 numeral 2.

In the form of device illustrated in Fig. 1 a bar of suitable metal 3, for example, wrought iron or steel is welded to the upper surface of one of the two oppositely extending flanges which make up the rail base. This bar or strip is preferably long enough to span two adjacent ties and may be made long enough to span more than two ties, if desired. It is provided with suitable spike 35 holes 4, whereby it may be spiked to two or more ties. The welding may be accomplished in various ways. For example, electric welding may be employed or a fusible mixture of iron oxide and aluminum may be used, or other welding processes may be employed. Where the welding is performed by the use of a fusible mixture of finely divided iron oxide and aluminum, the bar 3 is preferably provided with a hole, the upper 40 end of which is surrounded temporarily by a clay cup, the hole and the cup being filled with a mixture which, after being ignited, fuses said bar to said rail base, a small projecting mass of metal 5 being left after the

operation is completed. If the welding is 55 accomplished electrically, the bar is suitably clamped to the rail base in a well known manner and welded thereto by the passage of a heavy current through the contacting elements. In either case the bar is 60 integrally joined to the rail base and moves therewith when the rail tends to creep. The spikes 6, which are driven through the spike holes 4, transmit the creeping tendency to one or more ties, whereby the creeping is 65 effectually resisted. The form of anti-creeper just described is preferably applied to the rail directly opposite a rail joint, assuming the rails to be laid in the well known staggered arrangement. Creeping is 70 prevented at the rail joint itself as the fish plates are bolted to both rails and are also spiked to the ties. Accordingly, the creeping tendency is necessarily resisted by one end of the ties adjacent to the rail joint. 75 By arranging my improved anti-creeper opposite said rail joint creeping of the other rail is resisted by the other ends of said ties. I thereby provide against skewing of the ties and consequent disturbance of the gage. 80

The anti-creeper illustrated in Fig. 2 consists of a plate or bar 7 having preferably, one or more downwardly extending lugs or projections 8, which are preferably struck up from the metal of said plate or otherwise 85 formed integrally therewith. Each downwardly projecting element has a substantially vertical bearing face adapted to bear directly against the side of the corresponding tie and thereby transmit the thrust to 90 said tie independently of spikes, although spikes may also be employed, if desired. The downward projections may of course assume many different forms. The welded part in each case is to all intents and purposes a unitary part of the rail and accordingly never works loose and never permits the rail to slip with respect thereto. Furthermore, being placed against the upper surface of one of the rail flanges, it is in a 95 convenient position to be welded thereto. It is to be understood, of course, that both forms of device which I have described are selected simply for the purpose of illustrating the main features of the invention and for the purpose of suggesting a few of the 100 applications thereof. Accordingly, I do not limit myself to these forms, but I desire to 105

cover also any suitable equivalent means which fall within the scope of the appended claims.

What I claim as new and desire to secure by Letters Patent of the United States is:—

- 5 1. An anti-creeper for railroad rails comprising a member welded to the upper side of the rail base and extending over a plurality of ties, in combination with suitable 10 means for preventing relative longitudinal movement of said member with respect to said ties.
2. An anti-creeper for railroad rails com-

prising a flat bar welded to the upper surface of one of the rail base flanges, said bar 15 extending over a plurality of ties and extending laterally beyond the rail base, said bar having openings adjacent the outer edge of the rail base for the reception of spikes.

In witness whereof, I have hereunto subscribed my name in the presence of two witnesses.

CHARLES W. BREED.

Corrections in Letters Patent No. 1,075,187.

It is hereby certified that in Letters Patent No. 1,075,187, granted October 7, 1913, upon the application of Charles W. Breed, of Chicago, Illinois, for an improvement in "Anticreepers for Rails," errors appear in the printed specification requiring correction as follows: Page 1, line 32, after the word "example" strike out the comma; page 2, lines 8-9, for the words "a plurality of" read *one or more*; and same page, line 12, before the word "said" insert the words *at least one of*; and that the said Letters Patent should be read with these corrections therein that the same may conform to the record of the case in the Patent Office.

Signed and sealed this 28th day of October, A. D., 1913.
